UNITED STATES PATENT OFFICE.

FREDERICK C. McCLANAHAN, OF LITTLE ROCK, ARKANSAS.

ADJUSTABLE SCAFFOLDING.

1,251,066.

Specification of Letters Patent. Patented Dec. 25, 1917.

Application filed February 29, 1916. Serial No. 81,190.

To all whom it may concern:

Be it known that I, FREDERICK C. McCLANAHAN, a citizen of the United States, residing at Little Rock, in the county of Pulaski and State of Arkansas, have invented new and useful Improvements in Adjustable Scaffolding, of which the following is a specification.

This invention is an improved construction system, especially adapted for use in constructing silos and other like concrete structures and embodying a system of scaffolding, a hoisting mechanism combined therewith, and also embodying mold forms in which the concrete walls of the structure are molded.

One object of the invention is to provide an improved scaffolding system which embodies a plurality of scaffolds and means for raising and lowering them at will.

Another object of the invention is to provide a hoisting apparatus, which is combined with one of the scaffolds and is raised or lowered therewith.

Another object is to effect means in the construction of the scaffolds.

Another object of the invention is to effect improvements in the construction of the means for raising and lowering the scaffolds and hoisting the mechanism.

Another object is to effect improvements in the construction of the mold forms.

The invention consists in the construction, combination, and arrangement of devices, hereinafter described and claimed.

In the accompanying drawings:—

Figure 1 is an elevation of a concrete construction system embodying my invention and showing in cross section, the wall of a silo in course of construction.

Fig. 2 is a horizontal sectional view of the same on the plane indicated by the line *a—a* of Fig. 1.

Fig. 3 is a detail horizontal sectional view of the lower scaffold and through the mast.

Fig. 4 is a detail vertical sectional view of the upper portion of the mast, the upper scaffold, the hoisting boom and its connections and the hoisting mechanism.

Fig. 5 is a detail vertical transverse sectional view through one of the arms of the upper scaffold.

Figs. 6 and 7 are detail sectional views

respectively on the planes indicated on the lines *b—b* and *c—c* of Fig. 1.

Fig. 8 is a detail elevation of some of the mold sections.

Fig. 9 is partly an elevation and partly a sectional view of the core mold for use in the chute of a silo.

Figs. 10, 11, and 12 are detail views.

In the embodiment of the invention, I provide a mast 1 and a plurality of scaffolds which are slidably mounted on the mast and arranged to be raised or lowered as required. Two of such scaffolds are here shown, the lower scaffold being indicated at 2 and the upper scaffold at 3. The mast is preferably a steel or iron pipe of suitable dimensions and is provided at its upper end with a collar 4 having radial arms 5 to which suitable guys 6 are attached.

The lower scaffold has a centrally arranged tubular sleeve 7 through which the mast passes and which is adapted to be raised and lowered on the mast. Radially arranged bracket arms 8 are secured to said sleeve near its upper end and the inner ends of the arms 9 of the lower scaffold are secured to said bracket arms, each lower scaffold arm comprising a pair of L-bars 10 which are bolted together in spaced relation as at 11, and the inner ends of which are bolted on opposite sides of the bracket arms as at 12. Triangular attaching irons 12^a are riveted between the members of the arms 9 at points near their outer ends and the upper ends of braces 13 are riveted to said irons 12^a, said braces each comprising a pair of L-bars and their lower ends being bolted or riveted to radially arranged bracket arms 14 at the lower end of the tubular sleeve 7. Hence the lower scaffold is entirely carried by the sleeve 7 and may be raised and lowered therewith on the mast. Suitable flooring boards 15 are laid on and secured to the scaffold arms 9.

The upper scaffold has a tubular sleeve 16 which is longer than the sleeve 7 and is also arranged for vertical movement on the mast. The arms 17 of the upper scaffold each comprise a pair of spaced inverted L-bars 18, the inner ends of which are bolted to opposite sides of the bracket arms 19 which are secured to the lower portion of the sleeve 16. Each arm of the upper scaffold

also comprises a radially adjustable inverted T-member 20, the vertical web of which is arranged between the L-bars 18 and the horizontal web or tread of which is arranged to bear on rollers 21 which rollers are mounted for rotation on U-bolts 22 which are secured to the horizontal outstanding webs of the L-irons 18 as shown in detail at Fig. 5. Hence, each radial arm of the upper scaffold is adjustable longitudinally.

The sleeve 16 is provided at a suitable distance from its upper end with a collar 23 which has radial arms 24 and a track ring 25 on the upper side and at the outer ends of said arms. Braces 26 have their upper ends attached to the arms 24 as at 27 and have their lower ends attached by bolts 28 to plates 29 on the arms 17 of the upper scaffold, said plates being arranged in pairs and the lower ends of the braces being arranged between the said plates.

Near the upper end of the sleeve 16 are collars 30, 31. Said collars are respectively provided with radial arms 32, 33. A track ring 34 is attached to the lower ends of the arms 32 and a somewhat smaller track ring 35 is attached to the upper ends of the arms 33. A boom 36 which comprises a pair of spaced L-bars 37 has upper and lower bearing plates 38, 39, secured to its inner end by rivets or bolts 40. Peripherally grooved rollers 41 are mounted between said plates, on bolts 42 and engage the outer side of the track ring 25. A plate 42 is provided with an axle 43 on which peripherally grooved rollers 44, 45, are mounted, said rollers respectively engaging the track rings 34, 35, and said plate being arranged between said track rings. A brace 46 is provided for the boom and comprises a pair of L-bars 47. A hook 48 is bolted between said L-bars at their upper ends as at 49 and engages the plate 42 as at 50. A similar hook 51 is bolted between the lower ends of said L-bars and engage the boom and is connected thereto as at 52. A brace 53 has its upper end attached to the brace 46 and its lower end attached to the boom as shown. The boom may be turned in either direction as desired and may be swung around the mast. At the outer end of the boom is a pulley 54. A similar pulley 55 is mounted near the inner end of the boom. A pulley 56 is connected as at 57 to the lower end of the mast. A suitable hoisting cable 58 engages the pulleys 56, 55, 54, and a suitable bucket 58^a is suspended from the outer end of the cable by a bail 59 and may be used for hoisting concrete or other material as required in the building of the wall or other parts of the structure. A suitable lever 60 is provided for tilting the bucket to dump out its contents and is detachably fitted in socket pieces 61 with which the bucket is provided.

65 A safety grip to prevent the accidental

dropping of the tubular sleeve 16 and its connections is indicated at 113 in Fig. 1.

A pulley 63 is mounted at the upper end of the mast. Frames 64, 65, are bolted together and are also bolted to the lower portion of the sleeve 16 as at 66, said frames extending in opposite directions from the sleeve. A drum 67 is mounted in the frame 64 and its shaft is provided at one end with a spur gear 68 which is engaged by a pinion 69 on a shaft 70, said shaft being mounted in the sides of said frame 64 and being provided with a crank 71. A drum 72 is mounted in the frame 65 and has its shaft provided with a spur gear 73. Said gear is engaged by a pinion 74 on a shaft 75 which is mounted in the sides of said frame 65, the said shaft being provided at one end with a crank 76. A cable 77 for raising or lowering the sleeve 16 with the upper scaffold and also with the boom has one end attached as at 78 to the frame 64 and the other end attached to the drum 72, said cable passing over and engaging the pulley 63. Hence, by operating the drum 72 by means of the crank 76, and the connections hereinbefore described, the upper scaffold, together with the boom, may be raised or lowered as may be desired. A cable 79 is provided for raising or lowering the lower scaffold. The lower end of this cable is connected as at 80 to the lower sleeve 7 and its upper end is attached to the drum 67. Said drum may be operated by the crank 71 as will be understood, to raise or lower the lower scaffold.

The forms 81 for molding the concrete wall 82 of the structure are hoisted from time to time as the construction proceeds with the upper scaffold and by means of chains 82 attached to the extensible members 18 of said scaffold arms 17, and hooks 82, at the lower ends of said chains. Said hooks may be connected to eyes or clips 84 which are attached to reinforcing L-bars 85 of the mold sections 86, said mold sections being here shown as of oblong rectangular form and being metal plates of suitable dimensions and thickness, the said L-bars of the mold sections connected together by dowels 85, each dowel being headed in one L-bar and adapted to enter an opening in another. The L-bars of the mold sections are also connected together at the sides and ends of the mold sections by clamps 86, each of which comprises arms 87, 88, respectively, riveted to the L-bars, links 89 pivotally connected as at 90 to the plate 87 and a lever 91 pivotally connected as at 92 to the links and having an eccentric cam 93 for engagement with the arm 88. These clamps coact with the dowels in closely connecting the mold sections together.

Reinforcing elements 94 which are here shown as consisting of detachable links are held in position between the inner and outer

forms by brackets 95 and adjustable hooks 96. Each bracket has a hook shaped horizontal arm 97 to bear on the upper edge of the uppermost outside form and engage under the L-bar thereof and is provided with an opening through which one of the dowels extend. Each bracket also has a vertical arm 98 which overhangs the inner side of the outer form and extends upwardly therefrom and is provided with a series of adjusting openings 99, any one of which may be engaged by the substantially S-shaped upper arm 100 of the hook 96.

To mold the inner side of the chute 101 of the silo I provide a core mold 102 which comprises overlapping mold plates or sections 103 which have vertically arranged L-bars 104 on their inner sides near their overlapping edges. The outer ends of links 105 are arranged between said L-bars and pivotally connected thereto by bolts 106, the inner ends of said links being pivotally connected as at 107 to radial arms 108 on a vertically arranged central rod 109, which has a ring 110 at its upper end. By drawing said rod upwardly, the links serve to draw the mold sections 103 inwardly and thus permit the adjustment of the core mold in the chute and the progressive lifting of the core mold in the chute from time to time as the construction progresses. To prevent the links 105 from moving downwardly past a horizontal position, the rod 109 is provided with circular heads 111 to bear on said links as shown. A pipe 112 is arranged on the rod 109 and acts as a separator, holding the link or spreader arm units 105 in the required relative position. This core mold or chute form may be raised by the boom and cable 40 58 as will be understood.

In the operation of my apparatus, when constructing a concrete wall or the like, after all of the sections of the forms have been filled with concrete and the concrete is sufficiently set, the lower sections of outside forms are first secured by chains and hooks 82, 83, the clamps 86 are loosened, and the lower section thus permitted to expand and to be suspended from the arms of the upper scaffold by the chains 82 as will be understood. All the members of the lower section are raised in one operation and simultane-

ously. Small chains 112 are employed temporarily, loosely connecting the members of the form together.

For removing the inside forms, the lower section is released by first loosening the clamps on the vertical sides thereof. This permits one vertical division to be removed from place and afterward the other divisions may be released and set on the lower scaffold. The steel reinforcements hereinbefore described are placed, before the lower inside sections of the forms are raised.

When concrete or other material has been raised by the cable 58 and the boom, the bucket 58^a may be suspended from the boom by engaging its bail 59 with a hook 114 at the lower end of a chain 115 which hangs from the boom.

Having described the invention, what is claimed is:

1. In apparatus of the class described, a mast, a lower scaffold slidable vertically on the mast, a sleeve above the lower scaffold and slidable vertically on the mast, an upper scaffold and a frame mounted on said sleeve and movable therewith, a pair of drums mounted in said frame, a pulley on the upper end of the mast, a cable passing over said pulley, attached at one end to the frame and at the other end to one of the drums, for raising and lowering the upper scaffold together with said drums, and a second cable attached to the other drum and also to the lower scaffold to raise or lower the lower scaffold either simultaneously with or independently of the upper scaffold.

2. In apparatus of the class described, a scaffold having arms each comprising a pair of angle bars arranged in spaced relation, a radially adjustable cross sectionally T-shaped member having its vertical web arranged between said bars and its horizontal web arranged under said bars, and rollers on which said member bears, said rollers having U-shaped bearing and supporting members attached to said bars.

In testimony whereof I affix my signature in presence of two witnesses.

FREDERICK C. McCLANAHAN.
